SEALING WAD

Thomas H. Garber, United States Navy,
Washington, D. C.

Application May 31, 1945, Serial No. 596,947

8 Claims. (Cl. 102—95)

(Granted under the act of March 3, 1883, as
amended April 30, 1928; 370 O. G. 757)

1

This invention relates to ammunition and has particular relation to sealing wads for use in cartridge cases.

The principal purpose of conventional sealing wads is to provide a moisture protecting means for the impulse charges contained in cartridge cases. An additional purpose of sealing wads is to provide separator means between adjacent charges of unlike propellant powders, and they are also used as retaining means to confine impulse powder charges within a given space in a cartridge case. Conventional sealing wads are ordinarily composed of combustible material, such as readily ignitable cellulose nitrate, so as to permit combustion of the sealing wad when the powder charge is ignited. Immediate combustion of the sealing wad is essential to protect personnel and equipment in the vicinity from injury caused by flying pieces of the ejected sealing wad which have not been ignited or are not completely burned. Conventional sealing wads have the disadvantage that, after being blown from the cartridge case, either they are only partially burned or initial combustion does not take place. These conditions are dangerous not only because the flying particles of sealing wad are injurious to personnel and foul up equipment in the vicinity, but also because the flying particles which are still burning are a fire hazard. Furthermore, the flying particles of sealing wads which are still burning reveal the location of the firing to the enemy during battle, particularly at night. Thus, conventional sealing wads have failed to meet the conditions of service use either because they do not ignite at all, or because they do not ignite immediately or do not burn continuously, thereby resulting in incomplete combustion.

An object of this invention is to provide an ignitable sealing wad for use as a component in cartridge cases for depth charge projector impulse charges, torpedo impulse charges and the like.

Another object of the invention is to provide a sealing wad which will burn immediately and completely upon ignition thereof.

A further object of the invention is to provide a sealing wad which is of sturdy construction and yet can be immediately and completely burned in a minimum of time.

Still another object of the invention is to provide a sealing wad which occupies a minimum of space within a cartridge case and is economical to manufacture.

These and other objects of the invention will

be understood by reference to the accompanying description and drawing, in which

Fig. 1 is a longitudinal sectional view of a typical sealing wad of the present invention as positioned in a depth charge projector impulse charge cartridge case;

Figs. 2, 3, and 4 are exploded perspective views partially in section of the elements of the sealing wad shown in Fig. 1;

Fig. 5 is a sectional view of an inner sealing wad for use in a torpedo impulse charge;

Fig. 6 is a sectional view of a sealing wad having an annular, channel-shaped igniter portion; and

Fig. 7 is a sectional view of a torpedo impulse charge with an inner and outer sealing wad of the present invention mounted in place.

As shown in Fig. 1, the sealing wad of the present invention forms a closure component for an impulse cartridge case 10 ordinarily used in a depth charge projector. The cartridge case has a base 10a in which is secured a primer 11 for igniting a propellant powder charge 12. In one embodiment, the sealing wad of the present invention comprises a cup-shaped member 13 having a substantially flat base 13a provided with an air release vent 13b having a rim 13c terminating in an inturned edge 13d. The igniter portion 14 comprises a cup-shaped member of relatively thin cross-section having a flat base 14a provided with an air release vent 14b communicating with the vent 13b of the sealing wad cup member. The sides 14c of the igniter portion terminate in a thin edge 14d which is exposed to the powder charge 12. A seal disc 15 is cemented to the inner side of the base 13a over the vent 13b after assembly of the charge as will be hereinafter explained. For the purpose of definition, the igniter portion of contracted size 40 in each of its forms assumes an upstanding relationship to that face of the sealing wad which confronts the powder charge. Since it is of a flange or equivalent upstanding formation, as distinguished from a coating on the surface of 45 the sealing wad, it can be defined as a solitary eminence occupying the aforesaid face in a solitary locality.

In assembling the charge, the desired amount of propellant powder 12 is placed in the cartridge case. The igniter portion 14 is cemented to the outer base of the cup 13 so that the air release vents 13b and 14b are in communication. Any suitable cement such as nitro cellulose cement may be utilized for bonding these elements securely. It will be noticed that the sides 13c are

slanted at an angle greater than 90 degrees from the base 13a, as shown in Fig. 3, in order to provide secure engagement between the side and the wall of the cartridge case when the sealing wad is inserted therein. The sealing wad is inserted in the cartridge case so that the igniter portion 14 contacts the powder charge 12, the entrapped air being released through the vents 14b and 13b. The side of the sealing wad is bonded to the inner cartridge case wall with a waterproofing cement such as S-1503 manufactured by the Stoner-Mudge Company, Pittsburgh, Pennsylvania, as shown at 16. The seal disc 15 is then cemented to the inner side of the base 13 over the vent 13b, thereby sealing the powder charge within the cartridge case from contact with air, moisture, and foreign matter.

Further modifications of the sealing wads of the present invention are shown in Fig. 6. Referring to Fig. 6, the igniter portion 17 comprises an annular U-shaped channel of relatively thin cross-sections having a flat base 17a and sides 17b terminating in an exposed edge 17c. The igniter portion shown in Fig. 6 provides a greater surface of exposed edges than that shown in Figs. 1 and 2. This is of particular advantage when a small or defective powder charge is used or where the igniter portion is not directly in contact with the powder charge.

Referring now to Fig. 7, there is shown a portion of a torpedo impulse charge having a primer chamber 19, an outer sealing wad 20, and an inner sealing wad 22. The igniter portion of the outer sealing wad is generally similar to that shown in Figs. 1 and 3. The main body of the inner sealing wad 22, as shown in Fig. 5, has a center opening in the base defined by the in-turned flange 13e adapted to fit snugly against the primer chamber 19. The igniter portion comprises an annular cup-shaped flange of relatively thin cross-section. The base of the igniter portion 23 is provided with a central opening adapted to fit snugly about the primer chamber 19. The outer base of the igniter portion is securely cemented to the outer base of the cup 22 so that the upturned edge 23a of the igniter portion is in contact with the powder charge 12 when the sealing wad is inserted in the cartridge case over the primer chamber. When the igniter (not shown) is fired, it ignites the powder charge 12 through the vents 19b communicating with the chamber 19a. The upturned edge 23a, which is in contact with the burning powder 12, immediately initiates combustion of the sealing wad as it is blown from the cartridge case. A portion of the flame from the igniter passes along the chamber 19a contacting the igniter portion of the outer sealing wad 20 and the igniter portion thereof immediately initiates combustion of the outer sealing wad.

It is apparent that the ignition of the sealing wad must be instantaneous with the combustion of the powder charge caused by the ignition of the igniter. If instantaneous burning of the sealing wad does not take place, the wad will be blown from the cartridge case without having been ignited or ignition thereof will take place after the wad has been projected from the case. Either of the aforementioned conditions is unsatisfactory due to the danger of flying particles, either burning or unburned, which are projected from the case.

In order to provide instantaneous, continuous and complete burning of the sealing wad, it has been found that the cross-sectional width of the

cup member, and particularly of the igniter portion, must be held within critical limits. Thus, it has been found that the thickness of the cup member of the sealing wad must be no greater than approximately 0.05 inch in order to provide continuous and complete burning thereof. It has also been found that the thickness of the igniter portion edge should be approximately 0.01 inch although igniter portions having an edge thickness of not less than 0.008 inch nor more than 0.02 inch have been successfully used. The thickness of the seal disc is preferably approximately 0.03 inch. It has been found that if the thickness of the igniter portion edge is substantially less than 0.01 inch, continuous burning cannot be obtained; whereas, if the thickness is substantially greater than 0.01 inch, instantaneous ignition cannot be effected.

The sealing wad of the present invention is preferably composed of Celluloid or Pyralin, preferably a homogeneous nitro cellulose camphor compound. One composition which has proven particularly satisfactory is composed of approximately three parts nitro cellulose, approximately one part camphor, plus about .75% of the dry weight of nitro cellulose of urea, said components being dissolved in a suitable solvent. The nitro cellulose used is preferably prepared from cotton cellulose. It should have a nitrogen content of approximately 11% and should be at least 99% soluble in acetone and it should have a purification treatment of at least eight hours boiling at 100 degrees C. in acid water with an equivalent acid content equal to at least .05% sulfuric acid. The camphor used should be of such quality that a 20 gram sample, heated in a glass cup for four hours in a suitable oil bath at 150 degrees C., should show no discoloration. The urea should be neutral or very slightly alkaline and free from ammoniacal odor. The finished nitro cellulose should have a melting point of approximately 132 degrees C.

The invention herein described may be manufactured and used by or for the Government of the United States of America for governmental purposes without the payment of any royalties thereon or therefor.

I claim:

1. An ignitable and combustible sealing wad for use in a cartridge case, comprising a cup-shaped member having a substantially flat base provided with a solitary eminence on one side of said base, of contracted size relative to the size of the base to constitute an ignition portion for initiating combustion of the sealing wad.

2. An ignitable and combustible sealing wad for use in a cartridge case, comprising a cup-shaped member having a substantially flat base, and an igniter portion of relatively thin cross-section mounted on and projecting from the outer side of said base, said igniter portion being of contracted size as compared with the size of said base and therefore constituting a solitary eminence which is adapted to be packed in a contiguous powder charge for initiating combustion of the sealing wad from within the confines of said base when the powder charge is burned.

3. Means as set forth in claim 2 in which said igniter portion comprises at least one fin-shaped projection of relatively thin cross-section located medially of the boundary of said base and projecting from said base as a solitary eminence for initiating combustion of the sealing wad.

4. An ignitable and combustible sealing wad for use in a cartridge case, comprising a cup-

shaped member having a substantially flat base and an igniter portion comprising at least one fin-shaped circular projection of relatively thin cross-section mounted on and projecting from the outer side of said base for initiating combustion of the sealing wad.

5. An ignitable and combustible sealing wad for use in a cartridge case, comprising a cup-shaped member having a substantially flat base provided with an aperture and an igniter portion of relatively thin cross-section mounted on and having an aperture registering with the aperture in the base, said igniter portion projecting from the outer side of said base for initiating combustion of the sealing wad.

6. An ignitable and combustible sealing wad for use in a cartridge case, comprising a cup-shaped member having a substantially flat base and an igniter portion comprising a cup-shaped element of relatively thin cross-section having a substantially flat base, the outer side of said igniter portion being mounted onto the outer side of the base of said sealing wad, and the side of said igniter portion projecting away from the base of the sealing wad for initiating combustion of said sealing wad.

7. An ignitable and combustible sealing wad for use in a cartridge case, comprising a cup-shaped member having a substantially flat base and an igniter portion comprising an annular channel of relatively thin cross-section, the outer

5 side of said igniter portion being mounted onto the outer side of the base of said sealing wad and the sides of said channel projecting away from the base for initiating combustion of said sealing wad.

10 8. A sealing wad for use in a cartridge as a powder charge follower, comprising a combustible closure member adapted to be thrust into said case with one of its faces confronting the powder charge, and an igniter portion centered on said face, being spaced in from the boundary of and upstanding from said face in flange formation, said portion having a thin edge exposed to said powder charge.
